Patented Apr. 25, 1922.

Inventor:

K. B. WARNER

per Heatt Sutherland
Attorney.

UNITED STATES PATENT OFFICE.

KENNETH B. WARNER, OF HARTFORD, CONNECTICUT.

DESIGN FOR A FRATERNAL BUTTON.

60,923.

Specification for Design. Patented Apr. 25, 1922.

Application filed August 26, 1920. Serial No. 406,234. Term of patent 7 years.

To all whom it may concern:

Be it known that I, KENNETH B. WARNER, a citizen of the United States, residing in Hartford, county of Hartford, and State of Connecticut, have invented a new, original, and ornamental Design for a Fraternal Button, of which the following is a specification, reference being had to the accompanying drawing, forming part thereof.

The figure is a face view of a fraternal button, showing my design.

I claim:

The ornamental design for a fraternal button as shown.

KENNETH B. WARNER.
